UNITED STATES PATENT OFFICE.

HENRY CAVE, OF HARTFORD, CONNECTICUT, ASSIGNOR TO KNOX MOTORS COMPANY,
A CORPORATION OF MASSACHUSETTS.

TEA WAGON OR THE LIKE.

Application filed September 22, 1920. Serial No. 411,982.

To all whom it may concern:

Be it known that I, HENRY CAVE, a citizen of the United States, residing at Hartford, in the county of Hartford and State of Connecticut, have invented new and useful Improvements in a Tea Wagon or the like, of which the following is a specification.

This invention relates to improvements in tea wagons or the like and, while capable of general application, the invention may advantageously include means for performing a washing operation. That is, in addition to its use as a means for transporting dishes to and from the dining room, the invention in one of its aspects provides a receptacle to receive soiled dishes and these dishes may be washed in such receptacle.

The invention has for an object to provide in a device of the general nature of a tea wagon, having a member on which dishes may be transported, a tray arranged below such member and arranged for limited sliding movement with means for normally preventing removal of the tray.

Another object of the invention is to provide in a device of the class described, a wheeled supporting frame having a single pair of upright standards which support between them a hollow casing which is open at its upper end and the interior of which affords a receptacle for dishes and the like, and members mounted thereon and movable into one position, in which they close said open upper end and form a table for receiving and transporting the dishes and into another position in which they form shelves disposed at the sides of the casing.

Another object of the invention is to provide improved means for supporting said movable members in their shelf-forming positions.

Further objects of the invention relate to the details of construction and improved methods of operation, as will be more fully set forth in the detailed description to follow.

Referring to the drawings,—

Fig. 1 is a side elevational view, partially in section, of the washing machine;

Fig. 2 is a transverse sectional view of the machine taken substantially along the line 2—2 of Fig. 1;

Fig. 3 is a detail sectional view in plan

view illustrating the manner of supporting the upper edge portion of the tray from one end of the casing;

Fig. 4 is a top plan view of a portion of the machine when the covers are in closed position;

Fig. 5 is a detail end view of a portion of the machine showing the manner in which the brackets are telescoped within the hollow standards;

Fig. 6 is a vertical sectional view taken along the line 6—6 of Fig. 5;

Fig. 7 is a vertical sectional view taken along line 7—7 of Fig. 1;

Fig. 8 is a side elevational view of the receptacle and its associated mechanism which is provided for the removal of the heavier material for the dishes;

Fig. 9 is an end elevational view of the receptacle and its associated mechanism;

Fig. 10 is a detail view of the fastening mechanism employed for supporting the receptacle from the upwardly-extending plate;

Fig. 11 is a detail sectional view taken along line 11—11 of Fig. 4;

Fig. 12 is a detail sectional view taken along line 12—12 of Fig. 4; and

Fig. 13 is a vertical longitudinal sectional view of a slightly modified form of washing mechanism.

In the provision of machines of this character particularly adapted for family use, it is highly desirable to provide a structure readily moved from place to place, and possessing in addition to a receptacle for the dishes to be washed a suitable means for receiving and supporting the food which is to be moved from the table, thus making it unnecessary to transport the dishes to the place where they are to be washed and in addition remove and convey the food. Moreover, it is desirable that the machine be so constructed as to present a neat appearance and be capable of being moved from place to place after the manner of a tea wagon or similar structure.

It is to be understood that the machine shown and described is of such a type that after the dishes to be washed are suitably arranged therein it may be moved to the kitchen or wherever the washing operation is to be performed and there connected with a source of water supply, such as a suitable

pump, whereby wash water is sprayed upon the dishes and the cleansing of the dishes effected.

In the embodiment of the invention as illustrated herewith, 1 indicates generally the frame structure which comprises upright hollow standards 2 located at opposite ends of the washing machine, the standards being preferably formed of hollow pipe or tubing although they may be constructed in any manner or of any desired material, as circumstances may render expedient. A suitable frame, such as the substantially rectangular frame 3 shown, is secured to the upright standards 2, intermediate their ends, being so arranged relative to the standards as to occupy a substantially horizontal position. The rectangular frame above referred to may also be advantageously formed of hollow pipe or tubing after the manner of the upright standards. A caster 4 is swivelly connected to the lower end of each of the hollow standards, to assist in supporting the frame in such a manner as to permit it being readily moved from place to place. A U-shaped frame 5 is secured to the longitudinally-extending portions of the frame 3 adjacent the transverse center of the frame, each of the arms of the U-shaped member being provided with curved portions 6 partially surrounding the longitudinally-extending parts of the frame 3 and being secured thereto in any suitable or desired manner. The upwardly-extending arms of the U-shaped member 5 are each provided with vertical slots 7, which are located in substantial alignment with each other, and a shaft 8 extending transversely of the frame is positioned within the slot 7 for vertical movement therein. Depending brackets 9 are secured to opposite ends of the U-shaped frame member 5, and each of these brackets is provided with a caster 10 swivelly mounted therein and adapted to assist the casters 4 in normally providing a support for the frame. The shaft 8 projects beyond the parallel arms of the U-shaped frame member 5, and wheels 12 are rotatably mounted upon opposite ends of the shaft. The wheels 12 and casters 4 and 10 are preferably provided with rubber tires 13 in order to permit the machine to be readily transported from place to place upon polished floors without marring the same and also to prevent any possible sliding of the machine upon the floor or surface over which it is being transported. Rotatably mounted upon each end of the shaft 8, between the outer surface of the frame member 5 and wheels 12, is a member 14. These members 14 are in all respects of similar construction and each comprises a lever portion 15 extending in opposite directions from the shaft beyond the periphery of the wheel and provided at its opposite extremities with offset foot-

pieces 16 and 17, respectively. A cam 18 is firmly secured to the lever 15 in any desired manner and is provided with two or more surface depressions 19 and 20 located at different distances radially from the shaft 8, the cam member 18 being suitably positioned so that the surface depressions 19 and 20 may be selectively brought into engagement with a cylindrical projection 21 fixedly carried by the frame. A coil spring 22 may be secured at one end to the axle 8 and at its opposite end to a fixed part of the frame so as to normally tend to urge the depressions 19 to enter into engagement with the projections 21. It will be seen upon reference to Figs. 1 and 2 of the drawings, that by means of the mechanism just described, the lever 15 carried upon each side of the shaft may be actuated by moving the foot-pieces 16 or 17 to rotate the cam 18, thus bringing the surface depression 19 into engagement with the roller 21 and causing the shaft 8 to be forced downwardly in the slot a sufficient distance to bring the wheels 12 into engagement with the floor upon which the machine is standing, and thereafter raising the casters out of engagement with the floor and elevating the machine a sufficient distance so that when the wheels 12 are thus forced to their lowermost position the machine may rock about the shaft 8, which makes it particularly convenient for the machine to negotiate raised thresholds, edges of rugs, and the like.

A pair of angle-bars 24 are supported by the frame 3 adjacent the opposite ends thereof, and a tray 25 of substantially rectangular form is adapted to rest upon the angle-bars 24 and to slide thereon transversely of the frame. Brackets 26 and 27 are secured to opposite ends of the tray, at the corners thereof, and each of these brackets is provided with an offset lug 28 of circular form which projects inwardly toward the interior of the tray, and the lugs upon opposite sides of the tray at each end serve as trunnions for a sleeve-like handle 29. One handle 29 is located at each end of the tray, the handles being supported by the two brackets 26 and the two brackets 27, respectively. Each handle carries a pair of projecting lugs 30, the trunnions being located adjacent the opposite ends of each handle, and when the handles are in their normal position the trunnions occupy the position shown in full lines in Fig. 1 of the drawings. A lug 32 is carried by each of the upright standards 2 and is suitably located to engage the stop 30 carried by the handles as the tray is slid transversely of the frame when the handles 29 and stops 30 occupy their normal positions. Any suitable means may be employed for normally maintaining the handles 29 in such position as to bring the stops 30 into engagement with the lugs

32, such as the usual form of coil spring (not shown) which may be readily positioned within the handle 29 and have its opposite ends secured to the handle 29 and 5 trunnion 28, respectively.

By reason of this construction, the tray may be slid transversely of the machine for a limited distance, to facilitate loading and unloading but is normally prevented from 10 being completely removed from its supporting frame by the stops 30 engaging the lugs 32. When, however, it is desired to entirely remove the tray from its supporting frame, the operator may grasp the 15 handles 29, which extend transversely of the tray at opposite ends thereof, and by slightly rotating the handles bring the stops 30 into the position shown in dotted lines in Fig. 1 of the drawings, whereupon 20 the tray may be entirely removed from the supporting frame and be carried by the operator to such a place as it may be desired.

A substantially cylindrical casing member 35 is secured at its opposite ends to the upper ends of the upright standards 2, the upper end portion of said standards being flattened, as indicated at 36, to better facilitate their attachment to the end portions 30 of the casing. The flattened portions 36 of the standards may be secured to the casing in any suitable or desired manner, as by means of bolts or rivets 37, as indicated in Fig. 5 of the drawings. An opening 38 is formed in the upper end of each standard adjacent the flattened portion 36 to communicate with the hollow interior of each standard. A slideable bracket 40 provided at one end with an enlarged head 41 and at its opposite end with the angular portion 42 is adapted to project within the opening 38 and to normally telescope within the standard 2, whereby the angular portion 42 will occupy the position illustrated in 45 Figs. 5 and 6 of the drawings. These telescoping brackets are adapted to be partially withdrawn from the hollow standards, for a purpose which will be herein-after more fully described.

50 An elongated basket 44, preferably cylindrical and of foraminous material, such as wire mesh, is adapted to be positioned within the casing and supported entirely from one end thereof, thus leaving the opposite 55 end of the basket, as well as the side portions thereof, spaced a substantial distance from the opposite end and the sides of the casing. Any suitable means may be employed for thus supporting the basket from 60 the casing, and in the present instance this supporting means comprises a plate 45 firmly secured to the interior of the casing and provided with offset portions 46 adjacent its ends. The basket 44 is preferably 65 provided with a bead 47 of substantially

rigid material surrounding the upper edge thereof, and a plate 48 may be suitably secured to the basket adjacent the bead 47 and provided with lugs 49 for engaging the offset ends 46 of the plate to support the basket 70 from the casing. A spacing plate 50 may be secured to the interior of the casing below the plate 45 and engage the end portion of the basket in order to maintain the same in a substantially horizontal position. The 75 casing is provided with an opening adapted to be normally closed by means of cover members 51 and 52 hingedly supported by the end portions of the casing in a manner to be later described in detail. The cover 80 member 51 has a depressed portion 53 formed therein which serves as a means for lifting the cover member, and a similar depressed portion 54 is formed in the cover member 52 for a similar purpose. The inner 85 end of the cover member 51 is provided with a groove 55 formed by bending the metal, of which the cover member is made, back upon itself, and the flange 56 formed in the cover member 52 fits into the groove 55 90 when the cover members are in closed position to prevent the escape of the spray from the casing. A bead 57 extends around the inner surface of the cover member 51 adjacent the edge of the casing and serves the double purpose of interfitting with the upper edge of the casing to prevent the escape of spray when the cover member is closed. At its end, the bead 57 is extended 95 to form a pocket which serves as a means for catching any water which may run down upon the cover member when the cover is moved upwardly into a substantially vertical position and thus prevent this water from running down the outside of the casing or dropping upon the floor of the room. A similar beading 58, also bent to form a similar pocket, is formed in like manner upon the inner surface of the cover member 52 where it performs like functions. Similar pockets are provided adjacent the free end of each cover, which collect such water as may run down upon the cover when it is moved downwardly into a substantially 100 vertical position. All these pockets drain back into tank 35 when the covers are moved back into closed position. Brackets 60 are suitably secured to the outer surface of the casing at opposite ends near the upper edge thereof and extend outwardly and upwardly therefrom as shown in Figs. 1 and 4 of the drawings, the upper outwardly-extending end of these brackets being bent about a heavy wire 62 which extends around the side and end edges of the cover members 51 and 52 in order to form hinges for the cover members, thus enabling them to perfectly close the top of the casing. The wire 62 also serves to stiffen the cover members 105 and prevent them from bending when in 110

open position. These stiffening wires are secured to the side and one end portion of each cover member in any suitable manner, as by means of clips 65, and rubber or other cushioning material 66 surrounds the wires intermediate the clips to prevent the cover members which project beyond the outer edges of the casing from marring any portion of the woodwork of the room with which they may come into contact. Each bracket 60 thus serves as a hinge for one of the cover members, and the wire 62 carried by the corresponding cover member is enclosed within the bent portion of the bracket and rotates therein.

These cover members may each be held in horizontal position when open as indicated in dotted lines in Fig. 1 of the drawings, by means of the telescoping brackets 40 which, as previously described, are normally telescoped within the upright standards 2. When the cover member 51, for example, is open, the bracket 40 is drawn upwardly from out of the upright standard in which it is normally housed into the position shown in dotted lines in Fig. 1 of the drawings, whereupon the head 41 carried by the bracket abuts against the inner surface of the hollow standard and the loop-shaped portion 42 is then in position to engage the depression 53 formed in the cover and thus hold the same in substantially horizontal position, as shown in Fig. 1 of the drawings. When the cover members are thus held in horizontal position, a plurality of dishes may be set upon their upper surface, which serves as a table for supporting the same while they are being placed in position on the tray. The hinge arrangement for covers 51 and 52 is such that each may assume a third position, in which it extends downwardly and substantially vertically.

A suitable receptacle 70 is provided, to which is pivotally connected an upright plate 72 having a flange 73 extending around three sides thereof, the plate 72 being provided with suitable fastening means 74 by which it may be detachably secured to the upper edge of the basket, as indicated in Fig. 1 of the drawings. A suitable brush 75 is secured to the flange 73 at the upper edge of the plate 72 and projects beyond the edge of the flange for use in removing the heavier portion of the material upon the plates before the plates are positioned in the basket as illustrated in Fig. 9. A spout 76 having curved slots 77 formed in the side edges thereof is adapted to be placed in position relative to the plate 72 and supported by having the slots engage with projecting pins 78 carried by the side flanges 73 of the plate 72 so as to form a spout for directing the material removed by the brush 75 into the receptacle 70. This spout is capable of being readily removed from the plate 72 for

the purpose of cleaning the same by lifting it up slightly to disengage the pins 78 from the slots 77. The pivotal connection 79 by which the plate 72 is connected with the receptacle 70 may be of such a nature as to permit the ready separation of the plate from the receptacle in order that material in the receptacle may be removed therefrom and the plate and receptacle cleaned when necessary. A plurality of slats 81 are suitably mounted within the basket and serve as supports for the dishes A, which are preferably placed in substantially the position as shown in Fig. 2 of the drawings before the washing operation is commenced.

The means for conducting the wash water into the casing and spraying the same over the dishes is located or supported by the casing at the opposite end thereof from that to which the tray is attached, and comprises an angular pipe 84 provided with small openings 85 formed therein and extending substantially throughout its length, which pipe is supported by a spider 86 carrying rollers 87 adapted to run upon a track 88 carried upon the inner surface of the casing. A continuation 89 of the pipe 84 projects at right angles to the plane of the spider and is rotatably mounted in a bearing 90 carried by the wall of the casing. This continuation 89 of the main spray pipe 84 has an opening which communicates with a connection 92 fixedly secured to the casing, and suitable means may be employed to attach the portion of the pipe 89 to the connection 92 in such a manner as to permit free rotation of the pipe 84 without any leakage occurring at the point where the portion 89 joins the connection 92. A cup-shaped flange 94 may be secured to the outer surface of the casing surrounding the connection 92 to catch any water which may leak from the connection. An opening 96 is formed in the end portion of the casing through which a pipe may be inserted to draw water from the lower portion of the casing, and this water thus drawn from the lower portion of the casing may be forced by means of a suitable pump into the pipe 84 by means of a hose attached to the connection 92.

In the form of the apparatus illustrated in Fig. 1, the machine may be wheeled into the dining-room when the dishes are to be removed from the table, and the fact that the machine is mounted upon casters permits it to be turned in any direction or to be located in any position desired relative to the table. The dishes containing the food which are to be removed from the table may be readily removed from the table and placed in the tray 25, the tray being partially withdrawable from the tray upon which it is supported to make it more easy of access. The dishes to be washed may then be placed upon the cover members 51

and 52, which are preferably maintained in horizontal open position, as illustrated in Fig. 1, whereby they serve as shelves for supporting the dishes and from which each 5 dish may be taken separately and the heavier contents removed by bringing the same in contact with the brush 75, as shown in Fig. 9, and the dishes then placed in position in the basket. In placing the dishes in the 10 basket, the smaller articles, such as cups, may be placed bottom upward in the lower portion of the basket and the dishes inserted between the supporting strips 81 so that they occupy the position shown in Fig. 15 2. When the dishes to be washed have been entirely removed from the table and placed in position within the basket, the cover members may be closed, whereupon the brackets 40 can be telescoped within the 20 standards 2 and the machine may then be wheeled to the kitchen or any other place where the dishes are to be washed and the food contained in the tray 25 may be removed prior to the washing of the dishes. 25 In moving the machine from one room to the other, difficulty might be experienced in crossing raised thresholds and carpets, if the casters were wholly relied upon as means for supporting the same, but by de- 30 pressing the foot-pieces 17 the casters are thereby raised out of contact with the floor and the machine, being then capable of rock- 35 ing about shaft 8, can be readily pushed over rugs or thresholds without danger of the casters engaging the same and obstruct- 40 ing the movement of the machine.

In this form of the invention the washing operation is performed by connecting a source of water supply with the connection 40 92, whereby water is delivered under pressure to the spray-pipe, and the openings 85 in the spray-pipe, all extending in one direction relative to its axis of rotation, cause the pipe to rotate as the water is forced 45 therefrom through the openings.

In the modified form of the invention shown in Fig. 13, the casing 55 is in all respects similar to the casing previously described, and is supported by a pair of up-right standards 2 which are similar in all 50 respects to the standards previously de- 55 scribed and have flattened end portions 36 attached to the casing in the same manner as in the form shown in Fig. 1. These standards 2 are formed of hollow pipe or tubing, as in the form shown in Fig. 1, and telescoping brackets 40 are adapted to be housed therein for the purpose of supporting the cover members in a manner pre- 60 viously described. The cover members em- 65 ployed in this form of the invention are precisely similar to all those previously de- 70 scribed, but have been omitted from Fig. 13 75 of the drawings in order to more clearly

show the remaining mechanism. In this 80 form of this invention, the basket 44 is made in a similar manner to the basket previously described and differs therefrom only in that it may be supported from both ends of the casing. The means for supporting 85 the basket comprises plates 98 secured to the inner surface of the casing at opposite ends thereof, and each plate has its end portion spaced inwardly from the casing as indicated at 99. Plates 100 are secured to the opposite ends of the tray, and each of these plates is provided with brackets 101 adapted to extend over and engage the inwardly-offset portions 99 of the plates 98 to support the basket in a position within the 90 receptacle in such a manner as to permit the same to be readily removed. Aligned bearings 102 and 103 are formed in the opposite ends of the casing to rotatably support a U-shaped spray-pipe 104. Suitable stuff- 95 ing-boxes 105 and 106 may be provided to prevent water leaking around the bearings within which the U-shaped spray-pipe is rotatably mounted. A crank 107 is provided 100 which has a portion constructed to fit upon one end of the U-shaped spray-pipe, for the purpose of turning the pipe in its bearings, and the crank is also provided with a handle 108, as is usual in devices of this character. That portion of the U-shaped spray-pipe 105 which is mounted in the bearing 103 is in communication with an opening formed in a connection 109 which is fixedly secured to the casing whereby, when a hose is attached 105 to the connection 109, water may be pumped 110 into the spray-pipe and delivered therefrom through a plurality of minute openings 110 formed in the inner face of said U-shaped spray-pipe. An opening 112 communicates 115 with the interior of the casing at the lower portion thereof, through which a pipe may be inserted to draw water from the casing and return the same to the spray-pipe by means of a suitable pump mechanism. A 110 cup-shaped member 114 is secured to the outer surface of the casing surrounding the connection 109 to catch any water which may escape around the connection and prevent it from dropping to the floor of the 115 room.

In the operation of the construction de- 120 scribed above the crank 107 is placed in position to engage the U-shaped spray-pipe and swung back and forth by means of the handle 108, thus causing the spray-pipe 104 to be oscillated in its bearings backward and forward to spray water upon the dishes contained in the basket 44. In this form, as in that previously described, a separate pump- 125 ing unit may be employed in which a hose is connected with the pump to draw water from a pipe or other supply, and a hose connects the pump outlet with the connection

109 to supply water to the supply pipe. When a sufficient amount of water has been pumped in the casing through the spray-pipe, the hose connection which extends 5 from the pump inlet to the water supply is disconnected from the source of water supply and inserted in the opening 112, whereby water is drawn from the opening 112 and returned to the casing through the 10 spray-pipe 104 for a sufficient time to entirely clean the dishes contained in the tray. When the dishes have been completely washed or when it becomes desirable to employ fresh water in the washing operation, 15 the pump may be employed to remove the water from the casing through the opening 112 and fresh water may then be supplied to the spray-pipe 104 in the manner previously described. As the spray-pipe is oscillated 20 by the crank 107, it traverses an arc of nearly 360° and thus sprays water upon the dishes contained in the tray from an infinite number of different angles, thus insuring that the entire surface of each dish will be 25 subjected to the water spray and thus be entirely cleaned. The efficiency of the water spray is also enhanced by reason of the fact that since openings are formed both in the main portion of the U-shaped spray-pipe 30 and in the parallel end portions thereof the spray is delivered to the tray from three different sides thereof as well as from practically every angle during the oscillation of the spray-pipe.

35 What I claim is—

1. In combination, a supporting frame comprising a pair of upright standards, a casing carried by said standards, supporting members carried by the frame below 40 said casing, a tray slidably mounted upon said supporting members, cooperating means carried by the tray and standards, respectively, for preventing the removal of the tray from said supporting members, and 45 means for disengaging said cooperating

means comprising a pivoted member manually rotatable.

2. In combination, a wheeled supporting frame, an elongated casing carried by said frame and provided with an opening formed in the top thereof, a rail surrounding the opening formed in the top of said casing and having cushioning material applied thereto, and cover members hingedly supported by said rail adjacent the ends of 55 said casing.

3. In combination, a wheeled supporting frame, a casing carried by said frame and provided with an opening formed in the top thereof, cover members hingedly supported 60 by the casing at the opposite ends thereof, and extensible brackets carried within the frame and extensible therefrom for supporting said cover members in substantially horizontal position when the same are 65 swung from their closed position over the opening in the casing.

4. In combination, a wheeled supporting frame, a casing carried by said frame and provided with an opening formed in the top 70 thereof, and cover members hingedly supported by the casing at the opposite ends thereof and movable into and adapted to be supported in a vertical position and also in two positions 90° therefrom.

5. In combination, a wheeled supporting frame having hollow standards positioned at opposite ends thereof, a casing carried by said standards and provided with an opening formed in the top thereof, cover members hingedly supported from the ends of 80 said casing for closing the opening in the top, and brackets normally telescoping within said hollow standards and withdrawable therefrom to support said cover members in 85 substantially horizontal position when the cover members are swung from their closed position over the opening in said casing.

HENRY CAVE.
